(57) **CLAIM**

What is claimed is the ornamental design for an exercise handle, as shown and described.

DESCRIPTION

FIG. 1 is a front perspective view showing the exercise handle of Applicant's invention.

FIG. 2 is a top view of the exercise handle of Applicant's invention.

FIG. 3 is a front view of the exercise handle of Applicant's invention.

FIG. 4 is a right view of the exercise handle of Applicant's invention; and,

FIG. 5 is a view of the exercise handle of Applicant's invention in use.

The broken lines shown in the drawings depict environment and form no part of the claim.
